UNITED STATES PATENT OFFICE

159,719

TELESCOPE

Donald E. Davidson, Los Angeles County, Calif.

Application April 11, 1949, Serial No. 1,893

Term of patent 14 years

(Cl. D57—1)

To all whom it may concern:

Be it known that I, Donald E. Davidson, a citizen of the United States of America, residing in the county of Los Angeles, Los Angeles, State of California, have invented a new, original, and ornamental Design for a Telescope, of which the following is a specification, reference being had to the accompanying drawing, forming a part thereof.

Figure 1 is a side elevational view of a telescope, showing my new design;

Figure 2 is a top plan view thereof, a forward portion being broken away;

Figure 3 is a rear end elevational view thereof; and

Figure 4 is a fragmentary view of the rear end portion thereof looking along the axis of the eye piece.

I claim:

The ornamental design for a telescope, substantially as shown and described.

DONALD E. DAVIDSON.
